UNITED STATES PATENT OFFICE.

EDWARD BERNARD HESS AND LEWIS CARY MYERS, OF BROOKLYN, NEW YORK,
ASSIGNORS TO ROYAL TYPEWRITER COMPANY, INC., OF NEW YORK, N. Y.

LINE-SPACING MECHANISM FOR TYPEWRITING MACHINES.

1,417,907.

Specification of Letters Patent. Patented May 30, 1922.

Original application filed January 13, 1921. Serial No. 436,924. Divided and this application filed May 27, 1921. Serial No. 478,169.

To all whom it may concern:

Be it known that we, EDWARD BERNARD HESS and LEWIS CARY MYERS, both citizens of the United States, residing in Brooklyn, 5 county of Kings, city and State of New York, have invented certain new and useful Improvements in Line-Spacing Mechanism for Typewriting Machines, of which the following is a specification.

10 The application for this patent is a division of our application for patent filed Jan. 13, 1921, No. 436,924.

The object of this invention is to provide improved mechanism for turning or adjusting the platen for either single or double space line printing, and which is associated with means for returning the carriage to starting position and for preventing overthrow of the platen while being set.

20 According to this invention the platen is turned for line spacing by a lever which projects forwardly to a considerable extent from the platen so as to be within easy reach of the operator when actuating the platen 25 for line spacing and for returning the carriage to starting position. The lever operates a pawl which engages a ratchet wheel secured to the left-hand end of the platen. Overthrow of the platen is prevented by a 30 detent which engages the ratchet wheel and which is provided with an operating key by means of which it may be released from the ratchet wheel, when desired. In order to turn the platen for either single space or 35 double space line printing, we employ a lever projecting rearwardly from the platen shaft and carrying an arm having a curved member adapted to engage a pin carried by the pawl. By operating this lever the 40 toothed end of the pawl may be raised and lowered in such manner as to engage the next tooth on the ratchet wheel or to pass over a tooth and engage the second tooth; i. e., the pawl may be operated to effect either 45 single or double space line printing. The lever may be set in either position desired and held by improved locking devices.

In the accompanying drawings:—

Figure 1 shows a top plan view of part of 50 a typewriting machine platen with our improved line spacing devices applied.

Figure 2 shows an end view of the mechanism with the platen shaft in section.

Figure 3 is a view similar to Fig. 2 with the parts in a different position.

55

Figure 2 shows the parts set for single line spacing, and after the line space lever has been moved sufficiently to bring the pawl into engagement with the ratchet, while Figure 3 shows the parts set for double line 60 spacing and in normal position.

Figure 4 is a view of the mechanism looking towards the left hand end of the machine.

A portion of the platen is indicated at A. 65 a indicates the platen shaft and a' one of its operating knobs.

A lever B is pivoted at b to a bracket C on the left-hand side plate D of the carriage. The lever projects forwardly to a considerable extent from the platen, its end b' being within easy reach of the operator. The lever serves not only to operate the line-spacing devices but also to return the carriage to starting position. Said lever swings 70 about a vertical axis, limited by a downwardly extending arm d which engages the rear end of the bracket C on which the lever is pivoted. An arm b² of the lever B engages an upwardly extending arm of a lever 80 E, mounted to turn on a sleeve e, secured to the side plate D. The lever is pulled in one direction by a spring e', applied to its lower end.

The lever E carries a pawl F adapted to 85 engage a ratchet wheel G, securely fastened to the left-hand end of the platen. The pawl is drawn downwards towards the ratchet wheel by a coiled spring g and the upward movement of the pawl is limited by 90 a stop g' carried by the upper end of the lever E. When the lever B is moved from left to right it swings the lever E rearwards, causing the pawl to engage a tooth of the ratchet wheel and thus turn the 95 platen the desired distance. Afterwards the carriage is moved to starting position. The rearward movement of the pawl is limited by an adjustable eccentric stop H secured to the left-hand side plate D.

100 Overthrow of the platen is prevented by a detent I which engages the ratchet wheel

22

on its under side. This detent is pivoted at *i* to the adjacent side plate *D* and it has an arm *i'* to which is connected a coiled spring *J* which normally holds the detent in engagement with the ratchet wheel with a yielding pressure. In this way overthrow of the platen while being turned for line spacing is avoided and the platen is also normally held against movement except 10 when positively actuated.

When desired, the detent may be withdrawn from the ratchet for fractional spacing by a lever *K* having a finger-piece *K'* within convenient reach of the operator and 15 which is pivoted at *k* to the frame in rear of which pivot it has a cammed extension *k'* adapted to engage a pin *L* projecting laterally from the lower end of the detent lever. When the finger-piece is pushed in the extension *k'* engages the pin *L* and the detent 20 is withdrawn.

Means is provided whereby the platen may be turned for either single space or double space line printing. For this purpose we employ a lever *M* extending rearwardly from the shouldered nut *N* on the sleeve *e* and carrying an arm *M'* having a forwardly extending curved member or 25 pawl-lifting device *O* adapted to engage a pin *P* extending laterally from the pawl *F*. By turning this lever the toothed end of the pawl may be raised and lowered and set in such manner as to engage the next tooth on the ratchet wheel or to pass over a tooth 30 and engage the second tooth or the desired tooth; i. e., the pawl may be operated to effect single space or double space printing.

The lever *M* may be set in either position desired and held by a bur *m* on its side

which is adapted to engage an indentation 40 *n* in the side plate *D* of the carriage or a similar properly located indentation.

These devices in actual practice have been proved to be most efficient. They can be economically manufactured and easily assembled. 45

We claim as our invention:—

1. In a typewriting machine, a platen, a frame in which it is mounted, a ratchet wheel secured to the platen, a pawl adapted 50 to engage the wheel, a lever adapted to move about the axis of the platen, a lever for swinging said lever to cause the pawl to engage the ratchet and turn the platen, an adjustable stop for limiting the rearward movement of the pawl, a pin on the pawl, and a lever having an arm adapted to engage the pin to hold the pawl in proper position to engage the desired tooth of the ratchet wheel. 55

2. In a typewriting machine, a platen, a frame in which it is mounted, a ratchet wheel secured to the platen, a pawl adapted 60 to engage the wheel, a lever adapted to move about the axis of the platen, a lever for 65 swinging said lever to cause the pawl to engage the ratchet and turn the platen, a pin on the pawl, and a lever having an arm adapted to engage the pin to hold the pawl in proper position to engage the desired tooth of the ratchet wheel, said last-mentioned lever being held in place by burs and 70 dents in the lever and in the carriage frame.

In testimony whereof, we have hereunto subscribed our names,

EDWARD BERNARD HESS.
LEWIS CARY MYERS.
